UNITED STATES PATENT OFFICE.

PERCIVAL F. KING, OF NEW HAVEN, CONNECTICUT.

PLIER WRENCH.

Application filed August 11, 1924. Serial No. 731,424.

My invention relates to certain new and useful improvements in plier wrenches of the parallel jaw type, and it especially has for its object to provide such a wrench of a simple and effective construction that can be manufactured at low cost and which will have provisions for effecting a locking grip on the object being operated on.

Generically the tool comprises a body having a handle and a jaw in fixed relation thereto, another body with a jaw slidably mounted on the first body, a second handle pivoted to the first and having a portion to engage the slidably mounted body to open and close the jaws, the connection between the bodies being such that when the jaws are positioned into engagement with an object the reacting pressure will cause the body connection to effect a lock and hold the jaws against separation until spreading apart of the handles releases the same.

More specifically the invention includes those novel details of construction, combination, and arrangement of parts, which will be first fully described, then be specifically pointed out in the appended claims, reference being had to the accompanying drawing, in which:—

Fig. 1 is a side elevation of one embodiment of the invention,

Fig. 2 is a side elevation from the side opposite that shown in Fig. 1, and

Fig. 3 is a plan view of the same.

In the drawing in which like numerals of reference designate like parts in all the figures, 1 represents the fixed handle whose jaw 2 is laterally offset to provide the shoulder 3 against which a portion of the opposite body 4 is adapted to engage. The body 1 also has a portion to project into engagement with the shoulder 6 of the laterally offset jaw 5 of the body 4.

The body 4 has a recess or slot 7 having upper and lower curved faces 8 and 9 respectively to engage the finger 10 of the handle 11 which is pivoted at 12 to the handle 13 of the body 1, and by means of which handle 11 the body 4 will be caused to slide to move the jaw 5 toward and from the jaw 2.

In order to hold the two portions together and at the same time assist in providing an adequate locking means to hold the jaws in the gripping position, one of the bodies, say the body 1, is provided with a projection or horn 15 of rectangular cross-section

that works in an elongated slot 14 in the other body. The slot 14 of the width of the cross-section of the projection 15 extends in directions paralleling the shoulders 3 and 6, so that when the handles 11 and 13 are brought together to apply the jaws 2 and 5 to an object the reacting pressure will cause engagement between the point 17 and shoulder 3 and between the points 16—16^a of the projection 15 and the adjacent walls of the slot 14 and thus lock the jaws against separation until the finger 10 is brought into engagement with the curved portion 9 of the body 4 and the separating movement is applied to the handles to press the finger 10 against the curved portion 9, thereby rocking the movable jaw to disengage the surfaces 17 and 3 and the points of contact 16—16^a from the walls of the slot 14 and allow the jaw 5 to be moved away from the jaw 2 through this releasing of the locking pressures.

From the foregoing description, taken in connection with the accompanying drawing, it is thought the complete construction, operation, and advantages of the invention will be clear to those skilled in the art.

What I claim is:

1. In plier wrenches, a body having a jaw and a handle portion in rigid relation to the body, a second body having a jaw, means including a slot and a horn slidably connecting said bodies to cause the jaws relatively to move parallel, a handle pivoted to said first-mentioned handle, said second body having a portion projecting toward the pivotal connection and provided with a recess to receive one end of said pivoted handle, said recess lying between the place where the jaws are slidably connected and the place where the handles are pivoted together, said recess lying in alignment between said horn and the pivotal axis of the pivoted handle when the handles and jaws are closed together, said recess and said pivoted handle having a loose engagement, all being arranged whereby when the handles are opened they will cause the sliding jaw to rock in a direction opposite to the direction of the applied gripping force whereby to release the gripping action of the jaw connections, substantially as specified.

2. In plier wrenches, a body having a jaw and a handle portion in rigid relation to the body, a second body having a jaw, means slidably connecting said bodies to cause said

jaws relatively to move parallel, a handle pivoted to said first-mentioned handle, said second body having a recess to receive one end of said pivoted handle to open and close 5 the jaws, said connecting means comprising an approximately rectangular projection on one body, the other body having a recess to receive said projection, said projection having a slot extending in the direction of movement of the jaws, the body having the recess being provided with a horn passing through said slot, said handle receiving recess lying at a place located between the pivot of the handles and the place where the 10 jaw-connecting means is located, substantially as shown and described.

3. In plier wrenches, a body having a fixed jaw and a handle, a sliding jaw, means slidably connecting said sliding jaw to said fixed 20 jaw, a handle pivoted to said first-mentioned handle, said sliding jaw having a recess, said second-mentioned handle having a finger to enter said recess and move the sliding jaw in one direction or the other accordingly as 25 said handle is moved, said connecting means comprising a rectangular stud on one body, the other body having a rectangular slot to receive said stud, said slot extending in a direction parallel to the direction of move-

ment of the jaws, said stud and said slot 30 adapted to coact to lock said jaws against separation when gripping an object, said handle-receiving recess being located at a place between the pivot of the handles and the place where the jaw-connecting means 35 is located, substantially as specified.

4. In plier wrenches, a body, a handle and a jaw integrally formed, the jaw of said body extending laterally to provide a shoulder, a movable jaw associated with the jaw 40 of said body and including a body having a face to engage the shoulder of the first-mentioned jaw and lie flatwise against the body having the integral jaw, the body having the second-mentioned jaw also having a slot 45 extending parallel to said shoulder, said first-mentioned body having a rectangular horn projecting through said slot, the slotted body having a recess located in alignment with the jaw portion, a second handle member pivoted to the first-mentioned body and having a finger cooperatively engaging in said recess, the recess and finger lying in alignment between the pivot of the handle and the horn when the jaws are closed together, all being arranged substantially as 50 shown and for the purposes described.

PERCIVAL F. KING.
